TWO-STAGE PACKING WITH EQUALIZER CONNECTION

Harley T. Wheeler, Dallas, Tex., assignor to Elizabeth Wheeler, Dallas, Tex.

Application October 1, 1929, Serial No. 396,479

Renewed January 18, 1935

10 Claims. (Cl. 286—28)

This invention relates to a two-stage packing and equalizer connections for general use and refers more particularly to centrifugal and reciprocating rod packing and specifically to the formation of a tight joint between the moving and stationary parts of a machine with a low friction of contact.

One object of this invention is to provide a means of controlling the internal pressure of the assembled packing.

Another object is to provide an automatic device to regulate the seepage flow of the packing adjacent to the source of pressure.

Still another feature is its capability of determining and distributing the amount of friction to be created by the packing in the box.

Still another and important feature is the split-gland control by which the drop of pressure in each stage of packing may be adjusted to distribute the friction created over the area of packing surface.

I also desire to distribute the decrease in pressure as uniformly as possible along the rod so that the friction will not be excessive at any point.

The advantages of this invention will be more clearly observed, and further objects disclosed in the course of the following description, accompanied by the drawings wherein:

Fig. 1 is a sectional view of a stuffing box with the gland and equalizer connections in place.

Fig. 2 is a perspective of the spring nest.

Fig. 3 is a perspective of the packing follower.

Fig. 4 is a cross section of the spring nest assembly.

Fig. 5 is a cross sectional view of the expanding screw.

Fig. 5a is an end elevation of the expanding screw.

Fig. 6 is a perspective view of the gland.

Fig. 7 is a side elevation of the gland.

Fig. 8 is a plan view of two multiple stage pumps in series, showing the method of equalizing the two-stage packing internal pressures by connections to points in the pressure system.

My invention may be applied generally in stuffing boxes applied upon a moving rod or shaft and is illustrated herein particularly as connected with a high pressure pump or turbine and is understood as being connected at the outer end of the pump housing. The stuffing box 1 has on the inner side toward the pump housing an inwardly projecting partition or wall 1^a against which the packing may seat. On the outer end of the stuffing box is a radially projecting flange

or wall 1^b, furnishing a support for the clamping bolts 4 by means of which the packing gland 2 may be fixed or clamped tightly against the packing.

Said box and gland fit about a moving rod or shaft 3 and the gland is clamped inwardly against the packing by the bolts or screws 4 having nuts 5 on the outer end thereof.

The packing rings 6 employed in this invention are of porous fibrous material and preferably impregnated with a lubricant as will be later noted.

In carrying out my invention I provide a movable partition or adjustable gland 7, which is formed of ring shape and adapted to be clamped against the inner walls of the box by an expanding screw. With reference particularly to Figs. 6 and 7, it will be noted that the gland or partition is split longitudinally on the plane X and along this plane are inwardly tapered threaded openings to receive the expanding screws 8, said screws having polygonal recesses 9 therein to receive a wrench. The outer periphery of the gland is provided with a wide recess 7 extending entirely about the ring and forming a channel for the pressure fluid. There are also radial openings through the ring indicated at a in the drawings. These passages allow the pressure fluid escaping along the shaft to pass outwardly into the channel or groove 1.

In fixing this gland in the adjusted position, as shown in Fig. 1, by expanding the same by means of the screw 8, the same may be adjusted to register the channel 7 somewhere along the inner end of the vent provided by the threaded plug having the fluid outlet y therein. Said outlet is controlled by a valve 15 held in the outer end of the vent opening by means of a spring 20. There is a cap 11 over the outer end of the plug threaded to be adjustable along the plug to regulate the pressure of the spring 20. Said valve has a stem 16 projecting outwardly and about which the spring is located.

The plug is provided with a lateral outlet 18 into which is connected a pipe 19 leading to some portion of the pump or even to atmosphere where the pressure is lower than that in the stuffing box at that point.

At the inner end of the stuffing box I fix a spring nest whereby the packing rings on the inner side of the adjustable gland may be held under pressure. This nest consists of a ring 11, shown best in Fig. 3, of an outer diameter approximately the same as the inner diameter of the box and split longitudinally along an offset

line shown at 12^a. There are recesses 12^b on the inner side of the flange 11 into which the springs 12 may fit. The ring has a collar which is provided with an inner stop flange 11^b and 5 an intermediate stop flange 11^a. Along one side of the collar is a key 13 adapted to fit within a keyway 14 in the mating ring 10 shown in Fig. 2.

Said ring 10 is also longitudinally divided so as to allow the same to be fitted over the shaft, 10 said line of division being indicated at 12^a. There are also spring receiving recesses 12^b on the outer face of the said ring 10. When these two portions of the nest are fitted together as shown in Figs. 1 and 4, with the springs seated within 15 the recesses, the two partitions may be moved relative to each other with the ring 10 engaged between the inner flanges 11^a and 11^b, and limited in its longitudinal movement by said flanges.

It will be obvious that when the inner rings 6 20 are seated in the stuffing box against the spring nest the gland or partition 7 may be introduced and forced tightly against the packing rings so as to compress the springs 12 and thus place the packing rings 6 under compression. When the 25 proper pressure is obtained the gland 7 may be anchored in position by means of the expanding screw 8 and some portion of the outer channel 7 of said partition will register with the vent opening y previously described. The outer rings 6 30 will then be inserted within the box and the gland 2 clamped tightly against the same.

The packing rings 6 which I employ are of fibrous material impregnated with wax or oil. The purpose of these rings is to seal about the 35 rod to prevent leakage and to reduce the pressure of the fluid and transfer the thrust thereof to the frame of the machine. The impregnation of the packing is important in reducing the pressure along the length of the box. The oil or 40 wax is placed in liquid tension by the action of the pressure fluid and thus impedes the passage of the pressure fluid. The resistance of the impregnated pores of the packing to the passage 45 of the pressure fluid causes a pressure drop in the box. The flow of the pressure fluid through the pores is a seepage flow and should be distinguished from a leakage along the rod or the box wall.

In sealing the joint about the rod a friction of contact is created, that is, the ring structure 50 is pressed against the rod and stuffing box surfaces tight enough to delay, but not stop, the passage of pressure. The friction is coincident with the drop in pressure, the packing structure being elastic and reactive. The greatest friction 55 occurs where the drop of pressure occurs.

I find it desirable to distribute the drop of pressure in a porous packing at more than one point so that the reaction will occur at more than one point. I therefore employ the gland 7 and 60 arrange it to be adjustable so that it may be positioned to accommodate the thickness and form of the packing rings employed. When fixed in position it forms an intermediate stop or thrust member at that point. I desire to position 65 this gland so that the friction caused by the opposed sets of packing rings will be proportional to the number of rings employed in each set. I thus regulate the friction along the rod. Inasmuch as the seepage flow through a single set of 70 packing under several thousand pounds of pressure, for example, may not be more than one drop of liquid every fifteen minutes, the discharge through the automatic valve is figurative and all that the latter does is to establish a pressure level. What happens, as research has established,

is that if the seepage flow is too rapid the springs will compress the structure—if too slow, the packing expands and compresses the springs, so that the flow will increase. The pressure level establishes the rate of flow.

It should be obvious that at the gland position, the internal pressure should be a proportional value in relation to the length to establish a uniform drop throughout the structure. For example, for the gland in mid-position, the internal 10 pressure at the gland should be one-half the impressed pressure. Therefore, the automatic valve will be set to discharge any pressure more than one-half the value of that impressed, thus 15 controlling the drop of pressure across the inside set of rings which will cause one-half of the friction to be created by that same set. The outer set cannot create more friction than that due to one-half of the pressure impressed.

This device provides two points of thrust absorption which causes the pressure to drop at two points, the amount of friction being thereby distributed to occur half in each compartment, not possible with any single type set of porous packing.

The critical point of all packing operation is the amount of friction that occurs over the area. If a small length of the packing carries most of the friction, the heating and temperature, as well as the abrasive features will be greatest at 30 that point, so that regardless of the condition of the balance of the set, the point of highest friction controls the life, the adjustment and the general utility of the set. In this device it is not claimed to seal the joint with any less total friction, but to divide the friction producing areas into two sections, thereby distributing the friction and securing a coefficient at least one-half the value that is possible with a single set.

It will thus be seen that I can regulate the friction of the ring upon the shaft so that in no installation will the friction be excessive. The further advantages of the construction will be obvious to those skilled in the art.

I claim:

1. A packing device for rods including a stuffing box about the rod, a retaining rib at the inner end thereof, an adjustable gland at the opposite end of said stuffing box, an intermediate gland, means to fix said intermediate gland rigidly against longitudinal movement at any adjusted position in said box, compressible packing rings of porous material filling the space on opposite sides of said intermediate gland and adapted to be expanded by fluid pressure therein, a tensioning member between said packing and said rib, and means responsive to a predetermined pressure on said intermediate gland to relieve the fluid pressure at said gland, and thereby control the drop of internal pressure in said packing.

2. In a stuffing box for rods, a gland at the outer end thereof about said rod, a resilient support at the inner end, an intermediate adjustable partition fixed to the inner wall of said box, sets of compressible porous packing rings impregnated with a lubricant filling the space between said support and said partition and between said gland and said partition, said rings being adapted to be expanded through saturation 70 by pressure fluid therein and means to equalize the friction exerted on both sides of said partition on said rod.

3. In a stuffing box for rods and the like, a longitudinally divided gland between the ends of

- the box, means to fix said gland rigidly to said walls, porous packing rings filling said box at each side of said gland and adapted to permit a seepage flow of pressure fluid therethrough, 5 means to place said packing rings under compression to obtain a frictional contact with said rod and said box, and means to relieve the flow pressure at said gland.
4. In a stuffing box subjected to pressure, a flexible rod packing member compressed between the rod and stuffing box wall, a rigid partition frictionally fixed to the walls of said box to divide said packing member into an inner section and an outer section so that the friction of contact 10 created in each section is proportional to the drop of pressure within each said section, an automatic valve connected to the partition between said packing member sections responsive to a predetermined fluid pressure at said partition to 15 control the pressure level between the source of pressure and said partition, to thereby control the drop of internal pressure in said inner section and regulating the amount of friction created by said inner packing section.
5. In a stuffing box for rods and the like, a longitudinally adjustable partition between the ends of said box, means to fix said partition in the desired position, porous packing rings on both sides of said partition, resilient means to compress the rings on the inner side of said partition, a gland on the opposite side, and means to regulate the fluid pressure at said partition to a predetermined maximum.
6. In a stuffing box for rods and the like, a longitudinally adjustable partition between the ends of said box, means to fix said partition in the desired position, porous packing rings on both sides of said partition, resilient means to compress the rings on the inner side of said partition, a gland on the opposite side, and means to force said gland against the rings at the outer side of said partition to compress them independently of the rings on the inner side of said partition.
7. A packing device for rods including a stuff- 45
- ing box about the rod, an adjustable gland at the outer end of said stuffing box, an intermediate adjustable gland, means to fix said intermediate gland rigidly against longitudinal movement at any adjusted position in said box, compressible packing rings of porous material filling the space on opposite sides of said intermediate gland, and adapted to be expanded by fluid pressure therein, and means responsive to a predetermined pressure on said intermediate gland to relieve the fluid pressure at said gland, and thereby control the drop of internal pressure in said packing.
8. In a stuffing box for rods, a gland at the outer end thereof about said rod, an intermediate 15 adjustable partition fixed to the inner wall of said box, sets of compressible porous packing rings filling the space between said support and said partition and between said gland and said partition, said rings being adapted to be expanded through saturation by pressure fluid therein and means associated with said partition to relieve fluid pressure in excess of a predetermined amount exerted at both sides of said partition on said rod.
9. In a stuffing box for rods and the like, a longitudinally adjustable partition between the ends of said box, means to fix said partition in the desired position, packing rings on both sides of said partition, means to compress the rings on the inner side of said partition, a gland on the opposite side, means to force said gland against the rings at the outer side of said partition, and means to limit the fluid pressure within 30 said box along said rod.
10. In a stuffing box for rods and the like, a longitudinally adjustable partition between the ends of said box, means to fix said partition in the desired position, packing rings on both sides of said partition, means to compress the packing 40 longitudinally of said box, and a vent at said partition adapted to relieve fluid pressure only in excess of a predetermined amount.

HARLEY T. WHEELER. 45
